FRANKLIN E. ARNDT

By Attorney

UNITED STATES PATENT OFFICE.

FRANKLIN E. ARNDT, OF GALION, OHIO, ASSIGNOR TO GALION IRON WORKS, A CORPORATION OF OHIO.

CULVERT.

1,096,985.

Specification of Letters Patent.

Patented May 19, 1914.

Application filed November 3, 1913. Serial No. 798,874.

To all whom it may concern:

Be it known that I, FRANKLIN E. ARNDT, a citizen of the United States, residing at Galion, in the county of Crawford and State of Ohio, have invented certain new and useful Improvements in Culverts, of which the following is a specification.

This invention relates generally to pipes and mains and more particularly to sheet metal culvert pipes for light culvert and drain use, the same being preferably corrugated.

The invention has for its primary object a simple, strong, light, cheap, efficient and all-around serviceable corrugated culvert pipe formed out of semi-cylindrical sections of predetermined length capable of being shipped in nesting relation with each other, whereby freight charges are materially reduced, the parts being so constructed and arranged that they may be easily assembled at the point of installation so as to make a secure joint at the side seams and form a complete cylindrical pipe section without the necessity of special tools or of skilled labor. And the invention also aims to generally improve devices of this class so as to render them more useful and commercially desirable.

With these and other objects in view, as will more fully appear as the description proceeds, the invention consists in certain constructions, combinations and arrangements of the parts that I shall hereinafter more fully describe and claim.

For a full understanding of the invention, reference is to be had to the following description and accompanying drawing, in which—

Figure 1 is a side elevation of a culvert pipe embodying the improvements of my invention, one of the clamps being omitted to show the perforations and recesses in the sections. Fig. 2 is a fragmentary transverse sectional view thereof, and, Fig. 3 is a perspective view of one of the clamps detached.

Corresponding and like parts are referred to in the following description and designated in the accompanying drawing by like reference characters.

Referring to the drawing, the numeral 1 designates one of the semi-cylindrical corrugated pipe sections or parts preferably formed from sterling galvanized metal

sheet, each of said parts or sections being formed near both side edges and at predetermined points, longitudinally considered, with perforations 2 and at said edges and in circumferential alinement with said perforations, with edge opening and circumferentially elongated recesses 3.

4 designates clamps in the nature of tie bars which are preferably castings and which are formed at their ends with inwardly hooked or offset lugs 5 designed to enter the registering perforations of adjoining sections 1 when the parts are assembled to form a complete cylindrical culvert pipe. Each clamp is preferably formed at its middle with a boss, as shown, and an opening 6 extends through the boss from one side of the clamp to the other and is designed to receive the shank of a bolt 7, the head of the bolt being preferably disposed innermost and the outer threaded end receiving a binding nut 8 which screws up against the outer side of the clamp 4. The shank of the bolt 7 is also received or accommodated in the registering and overlapping edge recesses 3, which permit the overlapping edges of the assembled sections 1 to draw in one upon the other when the nut is tightened up with the lugs 5 in the perforations 2, while at the same time, the overlapping edges of the sections will be tightly pressed one against the other.

From the foregoing description in connection with the accompanying drawing, it will be understood that in the assembling of the parts, the semi-cylindrical sections will be fitted one upon the other to form the complete cylindrical structure with the side edges of the sections overlapping, and the clamps will then be placed in position, as clearly illustrated in the drawing, and the bolts passed outwardly from the inside and the nuts then applied, this entire operation being capable of being performed very quickly and expeditiously and without the necessity of special tools or skilled labor. As these sections are usually made in units of about, say, two feet in length, it will be seen that no trouble at all will be experienced in passing the bolts outwardly from the inside with the heads of the bolts abutting against the inner wall of the culvert pipe.

While the accompanying drawing illustrates what I believe to be the preferred embodiment of my invention, it is to be under-

stood that the invention is not limited thereto, as various changes may be made in the construction, arrangement and proportions of the parts without departing from the scope of the invention, as defined in the appended claims.

What I claim is:—

1. A culvert pipe made up of a number of sections overlapping at their side edges and formed in said overlapping edges with registering recesses and near said edges in circumferential alinement with said recesses, with perforations, clamps formed with lugs adapted to fit in said perforations with the clamps extending across the overlapping edges of the sections, the clamps being further formed with openings adapted to register with the recesses, and bolts receivable in said overlapping recesses and said openings and adapted to be secured to the clamps.
2. A culvert pipe made up of a number of sections overlapping at their side edges and formed in said edges with circumferentially elongated recesses and near said edges with perforations in circumferential alinement with said recesses, clamps adapted to extend across the overlapping edges and formed with lugs fitting in said perforations, and withdrawable means arranged to draw the

clamps inwardly toward the overlapping edges, said means being receivable in the edge recesses.

3. A culvert pipe made up of a number of sections overlapping at their side edges and formed in said edges with circumferentially elongated recesses and near said edges with perforations in circumferential alinement with the recesses, clamping bars adapted to extend across the overlapping side edges of the sections and formed at their ends with inwardly extending lugs receivable in said perforations and with middle openings adapted to register with the registering recesses in the overlapping edges, and bolts insertible through said recesses and the openings in the clamping bars, the heads of the bolts being disposed inwardly and abutting against the inner wall of the culvert pipe and the outer ends of the bolts being provided with nuts adapted to screw up against the outer sides of the clamping bars.

In testimony whereof I affix my signature in presence of two witnesses.

FRANKLIN E. ARNDT.

Witnesses:

W. J. GEER,
GARDA HOLMES.

It is hereby certified that the assignee in Letters Patent No. 1,096,985, granted May 19, 1914, upon the application of Franklin E. Arndt, of Galion, Ohio, for an improvement in "Culverts," was erroneously described and specified as "Galion Iron Works," whereas said assignee should have been described and specified as *The Galion Iron Works Company*, as shown by the records of assignments in this Office; and that the said Letters Patent should be read with this correction therein that the same may conform to the record of the case in the Patent Office.

Signed and sealed this 9th day of June, A. D., 1914.

[SEAL.]

J. T. NEWTON,

Acting Commissioner of Patents.
